UNITED STATES PATENT OFFICE.

ANDREW B. STEWART, OF CHICAGO, ILLINOIS, ASSIGNOR TO MECHANICAL PRODUCTS COMPANY, OF CHICAGO, ILLINOIS, A CORPORATION OF ILLINOIS.

DOOR-OPERATING MECHANISM.

Application filed June 26, 1917, Serial No. 176,987.

To all whom it may concern:

Be it known that I, ANDREW B. STEWART, a subject of the King of Great Britain, residing at Chicago, in the county of Cook and

5 State of Illinois, have invented certain new and useful Improvements in Door-Operating Mechanisms, of which the following is a specification.

This invention relates to a motor driven 10 apparatus for opening and closing a door, gate, shutter, or similar closure member, the word "door" being used throughout the following specification and claims to designate generically any movable closure of the general type indicated.

The invention is applicable to single and double doors, whether they be hinged, slideable horizontally or vertically, or foldable in sections, one section on the other. Illustrating the application of the invention to practical use, a typical door construction will be shown, with this understanding that the invention is not to be considered as limited to these particular constructions.

25 One of the principal objects of the invention is to provide motor driven means for opening and closing a door controllable from one or more points possibly remote from the door through the agency of momentarily energized control circuits by operation, for example, of push button circuit closers, the elements of said controlling mechanism being so constructed and arranged that the movement of the door in

30 opening or closing may be instantaneously arrested at any point and thereafter resumed either in the same or in the reverse direction. For example, with a plurality of sets of push button circuit closers arranged at different

35 points, which is the preferred arrangement, the opening or closing movement of the door may be initiated at one point, the movement interrupted by operation of the push button of a set located in a different place, the movement of the door resumed in either direction through the instrumentality of the appropriate push button of either of the first mentioned sets and that of the third set, if convenience or safety

40 45 50 should make such control of the apparatus desirable from different places. The device is not dependent upon any specified number of control sets; as many separate sets

may be used as is necessary. Nor is the operation of the device dependent upon the location of the control sets.

55 The invention provides, furthermore, for the automatic stoppage of the motor when the door reaches the limit of its movement in either direction.

60 A further object of the invention is the construction of the driving mechanism in such manner that the door or doors will be locked in any position in which their movement may be arrested, thus obviating the necessity for locking the doors by means of a separate lock. In addition, the invention 65 contemplates the provision of certain novel combinations of devices for providing the driving connection between the motor and the door or doors opened and closed thereby.

70 The invention is illustrated in certain typical embodiments in the accompanying drawings, wherein

75 Fig. 1 is an elevation of a vertically sliding and swinging door with the operating cables or belts attached thereto;

Fig. 2, a side elevation, partly in section, showing the door and the winding drums together with the operating cables;

80 Fig. 3, a detail view, partly in section, showing the connection of the elevating and lowering cables with the lower portion of the door;

Fig. 4 shows the conical shaped winding 85 drums with the driving motor attached thereto and shows, diagrammatically, the electric control circuits;

Figs. 5 and 6 illustrate, in plan and section, one form of relay; and

85 90 Fig. 7, a view, in perspective, of one of the door actuated circuit breakers.

95 Corresponding parts of the apparatus are indicated in the several figures of the drawings by the same reference characters.

Referring to the drawings, the door shown at 1 is a vertically sliding and swinging door which assumes a substantially horizontal position above the door opening when the door is open. Although I have shown a 100 door which is intended to slide vertically, it is obvious that the same arrangement of operating devices may be applied to a door which slides horizontally and assumes a position at substantially right angles to the 105 line of its closed position. I therefore do

- not desire to be limited to a door which slides vertically and assumes a substantially horizontal position above the door opening. The lower end of the door is constrained to move in a vertical direction by means of rollers 2 which engage both sides of vertical tracks 3 supported in a vertical position by members 4 secured to the sides of the door opening. The lower end of the door has a pivoted connection with the rollers 2 as shown at 5. The upper end of the door moves in a horizontal direction on tracks 6 which guide the rollers 7. The door is pivotally connected at 8 to the mechanism for moving the door along the track 6. The door is operated by means of the arrangement of pulleys, cables and winding drums shown in Figs. 1, 2 and 4. The lower end of the door is raised and lowered by means of cables 9 and 10 which run around pulleys 11 positioned below the lower end of the door. The connection of the cables 9 and 10 to the door is best illustrated in Fig. 3 which shows the pivot connection of the door 1. The cables 9 and 10 are secured to a ring 12 movably fastened to the door. This connection makes the cables 9 and 10, in effect, a single, continuous cable while permitting a simple and durable connection with the door. The raising cables 9 at both sides of the door pass around the pulleys 13 and 14 and are secured to the small ends of the outer spirally grooved winding drums 15 so as to wind under the same (Fig. 4). The lowering strands 10 at both sides of the door pass around pulleys 11, 16 and 17 and are secured to the large end of the spirally grooved winding drums 18 so as to wind over the tops of the same. As shown when the door is in its lowered or closed position, the strands 9 of the elevating cables are not wound around the drums 15 but the drums 18 are fully wound.
- I desire to be understood as using the word "cable" in its generical sense, i. e., to include any flexible element regardless of its material or cross-sectional configuration which accomplishes the same result.
- Cables for moving the upper end of the door inwardly and outwardly are shown at 19 and 20. The strand 19 of the cable is secured to the upper end of the door at 21 and passes around the pulley 22 located above the doorway. The strand 19 which operates to draw the door inwardly in order to open it is secured to the large end of the spirally grooved winding drum 23 and winds under the same, while the strand 20, which operates to assist in closing the door by passing around the pulley 22, is secured to the small end of the spirally grooved winding drum 24 so as to wind over the same end, as shown in Fig. 4, is fully wound around the drum when the door is closed. The operation of the door is easily understood from the draw-
- ings. The winding drums are cone-shaped for the purpose of imparting a variable movement to the upper and lower parts of the door. In order that the lower end of the door may be at first raised slowly, the elevating cables are attached to the small ends of the cone-shaped drums, and the lowering cables, which must be unwrapped as rapidly as the lifting cables are wound around the drums, are shown when the door is in closed position as unwinding from the drums at the small end. Upon opening the door the upper end of the door must be rapidly moved inwardly and accordingly the cable for imparting this movement to the door is shown as winding around the large end of the cone-shaped drum 23. The cable 20 is unwrapped as rapidly as the cable 19 is wound around the drum. When the door nearly reaches its open position it will be seen that the lower end is moving rapidly while the movement of the upper end is retarded. By this arrangement of winding drums all of the cables remain taut and the movement of the door is accelerated on opening and retarded on closing.
- The weight of the door is counterbalanced by the weight 25. This weight is secured to both sides of the door by means of the cables 26, 27. These cables pass around the double pulleys 28, 29. Cable 27 additionally passes around the pulley 30. These cables are secured at opposite sides of the door to the rings 12, as shown in Fig. 3.
- The door may be furnished with any suitable device for breaking the controlling circuits for the motor when the door reaches the limits of its movement in opposite directions. I have shown in Fig. 7 a device described later which may be used to accomplish this purpose, but it is evident that any circuit-breaking device which is actuated by the movement of the door on reaching its open or closed position may be used.
- The controlling mechanism for the motor 31, which will be next described, provides an arrangement of circuit and circuit governing devices whereby the momentary actuation of any of the door opening or closing push buttons 32 will initiate an opening or closing movement of the door, as the case may be, which is continued until the motor is automatically stopped on the completion of the intended travel of the door, or until one of these stop push buttons (which may be in the same set as the button previously actuated, or in any other set) is pressed, whereupon, in either case, movement of the door will instantaneously cease and the circuit governing elements of the controller be returned to their normal position so as to be ready to bring about the re-energization of the motor either to bring about a return of the door to its open or closed position, if the previous movement of

the door be completed, or, in case the movement of the door was arrested, the completion to effect either resumption of that movement in the same direction or a return of the door to its initial position. The convenience of this arrangement will be apparent. Suppose the door in question is a door of a public garage. When a customer wishes to drive his car out of the garage the attendant, by pushing the nearest door-opening push button, starts an opening movement of the door which requires no other attention on his part. The motor is automatically stopped when the door reaches its open position or just before that by contact with the upper circuit breaking device 33. When the door is to be closed, no re-setting of switches will be required; the nearest door-closing push button is pressed momentarily and the door closes. It may be of great importance, to avoid accidents, for example, to immediately stop the closing movement of the door. This can be done by pressing any one of the stop push buttons, and finally any one of the closing or opening push buttons may be pressed after the door has been thus stopped for the purpose of continuing movement in either direction desired.

30 The controlling mechanism by which the above stated operations are made possible is constructed as follows, reference being had particularly to Figs. 4, 5 and 6. The push button sets are shown in Fig. 4 at 32. Each set comprises three push buttons; those marked O are push buttons which close the circuit when pressed for opening the door; those marked C, when pressed, close the circuit to close the door; the push buttons S normally maintain the circuit closed but, when pressed, open the circuit for stopping the door in any position. These push buttons operate to close auxiliary circuits for the purpose of energizing the solenoids 34, 35. Current is obtained from any suitable source through the wires 36, 37. This current may be either alternating or direct current. The push buttons O of each set are connected in multiple, likewise the push buttons C of each set, but the push buttons S of each set are connected in series so that the pressing of any one of them will break the entire auxiliary circuit. The circuit of the push buttons S is also in series with the limit switches or making and breaking devices 33, so that the actuation of either the upper or lower limit switch marked U and L, respectively, in Fig. 4, also breaks the same auxiliary circuit.

35 The solenoids 34, 35 are provided with armatures 38, 39, to which are attached circuit closing disks 40, 41, 42, 43 by means of the rods 44, 45. The disks are maintained in position when the solenoids are de-energized in contact with the points 46, 47, etc., by means of the springs 52, 53. These springs are secured to the outer end of the rods 44, 45 and engage the supports 54, 55 at their inner ends. In order that the disks may fully contact with points 46, 47, etc., they are maintained in spaced relation by means of the springs 56, 57. The disks are loosely secured on the rods 44, 45 so that, by rotation, they may assume any position thereon. Their inward or outward movement is limited in each case by the pins 58. The disks are loosely mounted upon the rods 44, 45, as stated above, so that they may present clean surfaces of contact to the contact points. This is for the purpose of avoiding as much as possible the destructive action of the spark produced on opening the circuit by the inductive condition of the circuit.

40 Upon the energization of the solenoids the disks are drawn into contact with the inner pairs of contact points 59, 60, etc. The solenoids are mounted on a suitable base 65 so that they may be conveniently located with respect to the other door operating mechanism.

45 The operation of the electrical circuits is given as follows: Upon pressing the opening button O, for instance, the current passes along the wire 36 to the point Y, then along the wire 66 through the solenoid 35 and the wires 67, 68. The solenoid 34 being de-energized, the circuit is established through the disk 40 to the wire 69 through the switch O to the wires 70, 71, to the contact points 64, then through the wire 72, the upper limit switch 33, through all of the stop switches in series to the wire 73, then through the line wire 37. This establishes a circuit through the solenoid 35 and, accordingly, the armature 39 is drawn inwardly so that the disks 42, 43 make contact with the inner pairs of points 65, 66, 63, 64, respectively.

50 The excitation of solenoid 35 establishes two main circuits in parallel, the first circuit through the motor and the second circuit through the solenoid, the limit switches and the stop switches. The circuit through the motor is traced as follows: The current enters the wire 36 and enters the armature of the motor through the wire 74. The motor shown in Fig. 4 may be either an alternating current or direct current series motor. The current passes through the armature and out along the wire 75 to the contact point 49, then through the disk 41 which is in contact with the points 48, 49, to the series field of the motor by means of the wire 76 and out through the wire 77 to the contact point 66 on the relay. The bar 42 being in contact with the point 65, 66, the circuit is established through the point 65, 66 along the wires 78, 79 to the binding post X and out through the line wire 37.

55 The operation of the establishment of this

circuit causes the motor to rotate in a direction which opens the door.

The other circuit referred to which is in parallel with the motor circuit is traced as follows: The current enters the wire 36 to the binding post Y, thence through the wires 66, the solenoid 35, the wires 67, across the disk 43 which is now in contact with the points 63, 64 to the wire 72, then passes through the upper limit switch 23 and through all of the stop switches to the wire 73, then out to the other line wire 37. This circuit is provided for the purpose of maintaining the current through the solenoid 35 and thereby keeping the motor in operation. It will be noted that the breaking of this circuit by the operation of the upper limit switch or any of the stop switches will cause the spring 53 to draw the disks 42, 43 out of contact with the inner pairs of points and thereby break the circuit through the motor, causing the motor to stop.

The pressing of any of the push buttons C for closing the door will cause a similar operation of the solenoid 34. The operation of the solenoid 34 causes the motor to operate in the reverse direction and close the door. The reversal of the motor is accomplished in the usual manner by the reversal of the direction of current through the field with respect to the direction of the current through the armature. The outer sets of points controlled by the disks 41, 42 are connected for causing the reversing of the motor. The inner sets of points controlled by the disks 40 and 43 are connected with the push button sets and the solenoids. The circuits established by the pressing of any of the closing buttons C are as follows: from the closing button C the circuit is established through the lower limit switch 33 to the stop switches 8 in series, thence to the negative side of the line 37 to the positive side of the line to the point Y through the wire 66, the solenoid 34, the point 60 to the point 50, through the contact bar 43 and point 50 to the opposite side of the closing switches. The excitation of the solenoid 34 by means of the auxiliary circuit causes the bar 10 to make contact with the points 50 and 60 and the bar 41 with the points 61, 62. The operation of the solenoid in this manner establishes two main circuits in parallel; one through the solenoid which maintains it in its state of excitation, and the other through the motor for the purpose of operating the door. The first of these main circuits is traced as follows: from the opposite side of the line 36 to the point Y, through the wire 66, solenoid 34, to the point 60, through the bar 40 to the point 59, thence through the lower limit switch and the stop switches in series, and thence to the line wire 37. The other main circuit is traced as follows: from the line wire 36 the current enters

the motor through the wire 74 and passes on along the wire 75 to the point 49, thence to the point 52 through the bar 42, contact point 53, and thence through the wire 77 into the motor out along the wire 76 to 70 the point 61, through the bar 41 to the point 62, thence to the point X, and then out along the other line wire 37. It should be noted that the circuit through the solenoid 35 for instance, is controlled by the disk 40 operated by the solenoid 34. This arrangement of circuits is provided so that it is impossible to energize both of the solenoids at one time and thereby cause a short circuiting of the motor. It will be seen that if the solenoid 35 is actuated by the push button C at the time when the solenoid 34 is also energized, it will cause the de-energization of the solenoid 35 by breaking the circuit through the points 46, 47. It is possible, by this arrangement of circuits, to reverse the direction of the motor without first pressing any of the stop buttons.

In Fig. 7 I have shown a preferred construction of a door operated circuit-breaker, there being two of these circuit-breakers, one at the lower corner of the doorway adapted to be operated by one set of the rollers 2, and another so placed as to be operated by the same set of rollers when the door reaches its open position. These circuit-breakers are constructed as follows: 168 is a housing to which is pivoted on a stud 169 a switch arm 170 which is normally pressed against a rib 171 on the housing by means of a coil spring 172. The switch arm carries an insulating block 173 on which is an arcuate contact plate 174 adapted to be electrically connected with a pair of spaced fixed contact plates 175 which are arranged on an insulating block 176 within the housing 168. A rocking movement of the switch arm in the direction to carry it away from web 171 moves the contact plate 174 out of engagement with one of the fixed contacts 175, thereby breaking the circuit.

In Fig. 4 I have shown the winding drums driven by means of a spiral gear transmission. It is obvious that this form of drive may be applied to any of the doors described. The worm gear drive not only secures a considerable speed reduction, but also serves to lock the door in any position by merely stopping the motor. It will be seen, in Fig. 4, that the driving cables are wound around the drums several times. This prevents a slipping of the cables with respect to the drum and, accordingly, any attempt to open the door or alter its position when the motor is stopped is resisted by the driving drum through the worm gear transmission, it being impossible to rotate the motor by applying power to the drum. The coefficient of friction of the worm gear drive is sufficient to prevent rotation of the motor

by applying power to the winding drum shaft. The use of the operating mechanism to lock the door obviates the necessity of providing any other lock on the door. In fact, it is usual, in installing these devices, to remove the lock from the door. If a lock were necessary it would be objectionable because the doors could not be opened, in case they were locked, by the operation of a push button set remote from the door.

I claim:

1. In a sliding door, the combination of means for guiding one end of the door in the plane of the opening, means for guiding the other end of the door in a plane at an angle to the opening, a cable attached to the upper end of the door for imparting an initial opening movement in a direction away from the opening, a cable attached to the other end of the door for imparting an opening movement to the end of the door to which it is attached, and winding drums to which said cables are attached adapted to vary the speed of each of said cables attached to the upper and lower ends respectively of the door whereby the initial opening movement of the upper end of the door is faster than the initial opening movement of the lower end of the door, and whereby said cables will be maintained constantly taut while opening said door.

2. In a sliding door, the combination of means for guiding one end of the door in the plane of the opening, means for guiding the other end of the door in a plane at an angle to the opening, cables attached to opposite ends of the door for imparting an initial angular movement to the upper end of the door and for elevating the lower end thereof, respectively, and winding drums having conical surfaces on which said cables are wound, adapted to vary the speed of each of said cables connected to the upper and lower ends of the door, respectively, so that the initial movement of the upper end of the door will be faster than the initial movement of the lower end of the door during the opening movement, and whereby said cables will be maintained constantly taut.

3. In a sliding door, the combination of means for guiding the lower end of the door in the plane of the opening, means for guiding the upper end in a plane at an angle to the opening, a cable secured to the upper end for moving said end away and toward the opening, a cable secured to the other end, and operatively connected winding drums with which said cables are engaged adapted to vary the speed of each of said cables, said drums being so proportioned that said cables are kept constantly taut.

4. In a sliding door, the combination of means for guiding one end of the door in the plane of the opening, means for guiding the other end of the door in a plane at an

angle to the opening, cables secured to the upper end of said door for imparting positive opening and closing movements to said end, cables secured to the lower end for imparting positive opening and closing movements to the lower end, winding drums with which said cables are engaged, means for imparting the same angular velocity to said drums, said drums being so proportioned that said cables are kept constantly taut.

70

75

5. In a sliding door, the combination of means for guiding one end of the door in the plane of the opening, means for guiding the other end of the door in a plane at an angle to the opening, cables secured to both ends of the door which impart positive movements to both of said ends during the opening and closing of the door, and a winding drum shaft having winding drums thereon and with which said cables engage, said drums being so proportioned that said cables remain constantly taut while operating said door.

80

85

6. In a sliding door, the combination of means for guiding one end of the door in the plane of the opening, means for guiding the other end of the door in a plane at an angle to the opening, cables secured to both ends of the door for opening it, a winding drum shaft, and cone-shaped winding drums fixed on said shaft so as to operate in unison, the cable from one end of the door engaging, when the door is in a certain position, the small end of a drum, and the other cable engaging the large end of a drum, each cable advancing toward the opposite end of the corresponding drum when the door is operated whereby a variable positive movement is imparted to each end of said door.

90

95

7. In a sliding door, the combination of means for guiding one end of the door in the plane of the opening, means for guiding the other end of the door in a plane at an angle to the opening, opening and closing cables secured to the lower end of the door for imparting positive movement to raise and lower said end, an opening cable secured to the upper end of the door for imparting positive opening and closing movements to the said upper end, a winding drum shaft, and cone-shaped winding drums operated in unison thereon, the cables from one end of the door, when the door is closed, engaging the small ends of some of the drums, and the cables from the other end of the door engaging the large ends of other of said drums.

105

110

115

120

125

8. In a sliding door, the combination of means for guiding one end of the door in the plane of the opening, means for guiding the other end of the door in a plane at an angle to the opening, opening and closing cables secured to the lower end of the door for imparting positive movement to raise and lower said end, an opening and closing

130

cable secured to the upper end of the door for imparting positive opening and closing movements to the said upper end, a winding drum shaft, and cone-shaped winding drums for each of said cables adapted to operate in unison on said shaft and connected thereto, the opening cables from one end of the door, when it is in closed position, winding on the small end of the corresponding drums, closing cables from the same end unwinding from the small end of the corresponding drums, and the opening and closing cables from the other end of said door, respectively winding on and unwinding from the large ends of the corresponding drums.

9. In a sliding door which occupies, when open, a substantially horizontal position above the door opening, the combination of opening and closing cables secured to the lower end of the door for imparting positive movement to raise and lower said end, an opening and closing cable secured to the upper end of the door for imparting positive opening and closing movements to the said upper end, a winding drum shaft, cone-shaped winding drums for each of said cables adapted to operate in unison on said shaft, the opening and closing cables from the lower end of the door respectively winding on and unwinding from the small ends of the corresponding drums, and the opening and closing cables from the upper end of said door respectively winding on and

unwinding from the large ends of the corresponding drums.

10. The combination with a vertically sliding door, of a plurality of spirally grooved cone-shaped winding drums and means for operating them in unison, cables attached to the lower end of said door and to certain of said drums to impart positive movements to raise and lower the door, and other cables attached to the upper end of said door and to certain other of said drums for positively moving the upper end of the door inwardly or outwardly simultaneously with the raising or lowering of the door.

11. The combination with a door, of an electric motor adapted to operate in opposite directions, means connecting said door with the motor, and means for controlling the operation of the door comprising an electric circuit, a momentarily operable circuit closing device adapted when closed to energize the motor to open the door, a momentarily operable circuit closing device adapted when closed to energize the motor to close the door, circuit breaking devices adapted to be automatically actuated when the door reaches its open or closed position to de-energize said motor, and a circuit breaking device in series with the said automatically operable circuit breaking devices and adapted to be momentarily actuated manually to de-energize said motor.

ANDREW B. STEWART.

Certificate of Correction.

It is hereby certified that in Letters Patent No. 1,465,695, granted August 21, 1923, upon the application of Andrew B. Stewart, of Chicago, Illinois, for an improvement in "Door-Operating Mechanism," errors appear in the printed specification requiring correction as follows: Page 2, line 62, for the word "end" read *and*; page 6, line 28, claim 9, after the word "shaft" insert the words *and connected thereto*; and that the said Letters Patent should be read with these corrections therein that the same may conform to the record of the case in the Patent Office.

Signed and sealed this 6th day of November A. D. 1923.

[*SEAL.*]

KARL FENNING,
Acting Commissioner of Patents.
